(57) **CLAIM**

The ornamental design for a multi-sensor detector as shown and described.

DESCRIPTION

1. Multi-sensor detector

1.1 : Perspective

1.2 : Front

1.3 : Top

1.4 : Back

1.5 : Right

1.6 : Left

1.7 : Bottom

The broken lines in the reproductions depict portions of the multi-sensor detector that form no part of the claim.
